UNITED STATES PATENT OFFICE.

KARL MAYBACH, OF FRIEDRICHSHAFEN, GERMANY, ASSIGNOR TO THE FIRM:
MAYBACH MOTORENBAU GESELLSCHAFT MIT BESCHRANKTER HAFTUNG,
OF FRIEDRICHSHAFEN A/B., GERMANY.

MOTOR FEED REGULATING DEVICE.

Application filed September 27, 1921. Serial No. 503,669.

To all whom it may concern:

Be it known that I, KARL MAYBACH, a German citizen, residing at Friedrichshafen a/B., Germany, have invented certain new and useful Improvements in Motor-Feed Regulating Devices (for which I have filed applications in Germany September 6, 1920, and May 6, 1921), of which the following is a specification.

10 My invention refers to motor cars and other motor driven vehicles and more particularly to a special modification of the so-called accelerator serving for entirely cutting out the fuel supply as often as possible.

15 As is well known to those skilled in the art, the accelerator is a pedal lever serving to regulate the supply of combustible mixture to the motor. In the cars at present in use, when the accelerator is in the position

20 of rest, the carburettor is still so far opened that the motor is still capable of running with no-load and at the lowest possible number of revolutions. By actuating the accelerator, viz. by pressing the pedal lever

25 down, the throttle of the carburettor is opened more and more. On being released the accelerator automatically returns to its no-load position.

Up till now the accelerator was required 30 to act in this manner inasmuch as at the moment of changing over and consequently throwing out the coupling, the motor must not come to a stop. On the other hand, this involves the drawback that also in all other 35 cases, e. g., in descending a slope with the coupling thrown in the motor will permanently be supplied with some combustible mixture. In a case like this the consumption of fuel is even higher than it would be 40 with the motor running under no-load inasmuch as at the higher number of revolutions imparted to it by the car the motor exerts a considerably greater sucking effect than on normal no-load running with a lower

45 number of revolutions. It is moreover desirable that just in descending a slope the motor, instead of being supplied with fuel and being operated thereby, should exert a braking effect on the car.

50 All these drawbacks are obviated according to the present invention by imparting to the accelerator a position of rest in which it shuts off the supply of gas to the motor. Preferably the accelerator is locked in this

position in such manner as to be easily released, the locking device preventing it from moving back beyond the no-load position into the shut-off position or carrying it back from this shut-off position into the no-load position whenever the motor coupling is thrown out or when the starting device is being used.

In the preferred form of my invention I provide means for automatically releasing the locking device which prevents the accelerator from moving back into the shut-off position, whenever the accelerator is being used for increasing the output of the motor.

In the drawings affixed to this specification and forming part thereof, two modifications of the device embodying my invention are illustrated diagrammatically by way of example. In the drawings

Fig. 1 is an elevation of one modification which merely discloses the connection between the accelerator and the coupling.

Fig. 2 is a diagram of another modification showing the connection between the accelerator and the coupling as well as the starting device, and further the means for releasing the locking device of the accelerator whenever this latter has been brought to act.

Referring to Fig. 1, the accelerator *a* rocks about the axle *b* carrying the carburettor lever *c* and a lever *m* acted upon by the spring *d* which causes lever *a* on being released to move into the no-load and shut-off positions respectively. Lever *c* actuates by means of rod *e* the throttle of the carburettor (not shown). The accelerator lever *a* is represented in three different positions (*a*, *a*¹, *a*²), the position *a* corresponds to the shut-off position, in which the carburettor is completely closed and no gas is supplied to the motor, while *a*¹ corresponds to the no-load position, in which the carburettor allows only so much combustible mixture to pass to the motor as is required for light running. *a*² corresponds to the open position where the carburettor is completely open.

The clutch pedal *f* is fixed on the axle *g* and by turning this axle actuates the lever *h* and the clutch *l*. The clutch pedal *f* and the lever *h* are also represented in three different positions *f*, *f*¹, *f*² and *h*, *h*¹, *h*², position *f* being the throw-in position, while *f*¹

corresponds to that position of the clutch pedal, in which the clutch just begins being released and position f^2 corresponds to the position where the clutch is thrown out entirely.

According to the present invention now the clutch pedal axle g carries a further lever i provided with a stop k which extends across the accelerator lever a . That part of lever a on which the stop k glides, is formed like a guide in such manner that when the coupling is thrown in, the accelerator is free to move back to the shut-off position, being however carried from the shut-off position 15 into the no-load position as soon as the clutch is thrown out, this being effected by the stop k , on the clutch pedal being forced downwards gradually assuming the position k^1 and thereby causing lever a to assume the 20 position a^1 . The operation of this device is as follows:

With the clutch thrown in (position f of the pedal lever) the accelerator can be actuated as desired, namely it can assume all 25 three end positions a , a^1 , a^2 . However, as soon as it is released no matter what position it had assumed, the spring d will carry it automatically back into the shut-off position a . In case now that in this position of 30 the accelerator the coupling be thrown out, f. i. in order to change speed, the accelerator is forcibly carried by the stop k into its no-load position a^1 , the accelerator reaching this position at the moment at which the 35 clutch is just beginning to be released (position f^1 of the pedal lever) so that in this manner a stopping of the motor is effectively avoided.

In the modification shown in Fig. 2 the 40 accelerator is carried automatically from the shut-off position into the no-load position whenever the device for starting the motor is used.

Referring to Fig. 2, a bell crank lever is 45 pivoted at q above the accelerator lever a , one arm s of the bell crank lever cooperating with the accelerator lever a , its other arm t with the device for starting the motor. Of this device the drawing only shows the casing u of a pedal switch carrying the press button v which on being depressed by foot will throw in and start the electric starting motor which then causes the driving motor of the car to be started, until this latter 50 motor has reached the number of revolutions required. The rod w carrying the button v passes through the casing u and rests on the arm t of the bell crank lever whenever the button v is pressed down and the starting 55 motor is being operated. The arm s of the bell crank lever is then carried against the action of the spring x into the position shown in dotted lines and by pressing on lever a forces it to assume the position a^1 . 60 In this position the arm s of the bell crank 65

lever is caught by nose y which prevents the spring x from pulling the lever back into its original position even in case that the button v has been released and has been carried back into its position of rest.

70

The device described causes the accelerator lever a to be automatically carried from the shut-off position into the no-load position a as soon as the motor is being started. In consequence thereof the motor on being 75 started is supplied with so much combustible mixture as it requires for no-load running, this being continued so long until in order to start the car running, the accelerator lever a is moved on towards the position a^2 . 80 When this is being done, the nose y will release the arm s and allow the bell crank lever to return into its position of rest, thus allowing the operator to return the accelerator lever a , for instance on descending a slope 85 to its position of rest where the motor is stopped altogether.

As described above, with regard to the electric starting motor, in the case where the motor is started by hand, a pin may be provided which is moved at the well known 90 axial movement of the starting crank when this latter is coupled with the starting clutch, such pin exerting the same effect as the pin w shown in Fig. 2. The pin r shown in the drawing is designed to represent such a device. In the case where both an electric and a hand starting device are provided, both these pins may be provided as shown in 95 the drawing.

100

In order to influence the locking device for the accelerator by aid of the clutch, a cam disc n is fixed to the clutch pedal f , the cam o serving on the clutch pedal being depressed to press the arm t of the bell crank 105 lever down by aid of pin p , thus causing the pins to cooperate as described above.

The clutch pedal may thus be caused to act on the accelerator lever of some other device.

110

It is not necessary that the accelerator lever remains in the position a^1 corresponding to light running of the motor, when the clutch pedal f is released.

I wish it to be understood that I do not 115 desire to be limited to the exact details of construction shown and described, for obvious modifications will occur to a person skilled in the art.

I claim:

1. In a motor vehicle in combination, a motor, a motor shaft, a power transmitting shaft and a clutch adapted to couple said shafts, means for supplying fuel to said motor, a pedal lever for influencing said fuel supply means and adapted, when in its position of rest, to entirely throw out said supplying means and locking means adapted to prevent said lever from returning of itself into said position of rest, said locking means 120

120

125

130

being effective when said shafts are uncoupled.

2. In a motor vehicle in combination, a motor, a motor shaft, a power transmitting shaft and a clutch adapted to couple said shafts, means for supplying fuel to said motor, a pedal lever for influencing said fuel supply means and adapted, when in its position of rest, to entirely throw out said supplying means and locking means adapted to prevent said lever from returning of itself into said position of rest, said locking means being adapted to force said lever from its position of rest into no-load position 10 when said shafts are uncoupled, said locking means being effective when said shafts are uncoupled.

3. In a motor vehicle in combination, a motor, a motor shaft, a power transmitting shaft and a clutch adapted to couple said shafts, means for supplying fuel to said motor, a pedal lever for influencing said fuel supply means and adapted, when in its position of rest, to entirely throw out said supplying means and locking means adapted to prevent said lever from returning of itself into said position of rest, said locking means being effective when said shafts are uncoupled and a starting device connected 25 with said locking means in such manner that on said starting device being actuated, said lever is carried into no-load position.

4. In a motor vehicle in combination, a motor, a motor shaft, a power transmitting

shaft and a clutch adapted to couple said shafts, means for supplying fuel to said motor, a pedal lever for influencing said fuel supply means and adapted, when in its position of rest, to entirely throw out said supplying means and locking means adapted to prevent said lever from returning of itself into said position of rest, said locking means being effective when said shafts are uncoupled, a starting device and a stop adapted, on said starting device being actuated, to move said lever into no-load position and to be locked by said lever, until this latter is moved further.

5. In a motor vehicle in combination, a motor, a motor shaft, a power transmitting shaft and a clutch adapted to couple said shafts, means for supplying fuel to said motor, a pedal lever for influencing said fuel supply means and adapted, when in its position of rest, to entirely throw out said supplying means and locking means adapted to prevent said lever from returning of itself into said position of rest, said locking means being effective when said shafts are uncoupled, a starting device and a member connected with said starting device and adapted, on said starting device being actuated, to move said lever into no-load position and to be locked by said lever until this latter is moved further.

In testimony whereof I affix my signature.

KARL MAYBACH.
